UNITED STATES PATENT OFFICE.

ALBERT C. LINDBLOOM, OF CHICAGO, ILLINOIS.

PACKING DEVICE FOR VALVE STEMS.

Application filed June 5, 1922. Serial No. 565,832.

To all whom it may concern:

Be it known that I, ALBERT C. LINDBLOOM, a citizen of the United States, residing at Chicago, in the county of Cook and State 5 of Illinois, have invented a new and useful Improvement in Packing Devices for Valve Stems, of which the following is a specification.

This invention relates to packing devices 10 for valve stems of automobiles and the like, and is fully described in the accompanying drawing, in which the figure shows a longitudinal section through a valve stem having the invention mounted thereon.

15 The embodiment is illustrated in connection with a valve 10 having a valve stem 11 slidably mounted in the casting 12 and held upon its seat 13 by means of a spring 14, which is secured in a well known manner 20 to the lower part of the stem by means of the washer 15 and pin 16.

This valve is raised in any well known manner as by means of the valve tappet 17, which is periodically raised by means of a 25 cam shaft, not shown. It will be understood that the foregoing is well known practice in automobile construction.

In the case of the inlet valve, the passage A is under a greater or less degree of 30 vacuum and when the engine is new the valve stem 11 fits its seat fairly snugly so that only a small amount of air is permitted to leak therearound. As the engine is used, however, both the valve stem 11 and 35 the hole 11^a, in which it is guided, wear and as this wear increases the amount of air drawn into the passage A, around the valve stem 11, eventually becomes sufficient to 40 disturb the mixture of air and fuel reaching the engine and cylinder.

I have overcome this trouble by removing the valve stem 10 and placing thereon a pad 45 of yieldable material 18, such as felt or asbestos, together with a washer 19, which is preferably made concaved or conical on its inner surface and which is pressed down upon the material 18 by a spring 20, which is sufficiently stiff to maintain a pressure upon the washer 19 at all operative positions 50 of the valve 10 but which is a much weaker spring than the valve spring 14, so that it has no tendency whatever to alone raise the valve off its seat or until compressed by the valve tappet 17.

55 The compression of the felt-like material 18 squeezes it about the valve stem 11 so

as to greatly retard the tendency for air to flow around the valve stem. This action is increased by making the interfaces of the washer 19 concaved or conical. 60

This construction may be used upon either the inlet or exhaust valves. When used upon the exhaust valves, however, a non-combustible material, such as asbestos, must be used for packing. 65

While I have shown and described certain embodiments of my invention, it is to be understood that it is capable of many modifications. Changes, therefore, in the construction and arrangement may be made 70 without departing from the spirit and scope of the invention as disclosed in the appended claims, in which it is my intention to claim all novelty inherent in my invention as broadly as possible in view of the prior art. 75

What I claim as new and desire to secure by Letters Patent, is:

1. Means for packing the valve stems of internal combustion engines comprising a felt like material adapted to surround said 80 valve stem within the intake passage of the engine and a spring adapted to extend between the valve and said material for compressing the material about said valve stem. 85

2. In combination, an internal combustion engine cylinder having a valve guide, a valve having a stem slidable therein, a spring for normally holding said valve on its seat, packing surrounding said stem, within the intake passage of the engine and means for yieldably compressing said packing against said guide. 90

3. In combination, an internal combustion engine cylinder having a valve guide, 95 a valve having a stem slidable therein, a spring for normally holding said valve on its seat, packing surrounding said stem, within the intake passage of the engine and a spring for compressing said packing against 100 said guide.

4. In combination, an internal combustion engine cylinder having a valve guide, a valve having a stem slidable therein, a spring for normally holding said valve on its seat, packing surrounding said stem, within the intake passage of the engine and a spring weaker than the first mentioned spring surrounding said stem, one end of said weaker spring engaging the valve while the other compresses the packing about 105 said stem.

5. In combination, an internal combustion engine cylinder having a valve guide, a valve having a stem slidable therein, a spring for normally holding said valve on its seat, packing surrounding said stem, within the intake passage of the engine, a dished washer surrounding said packing,

and a spring weaker than the first mentioned spring surrounding said stem, one end of said weaker spring engaging the valve 10 while the other end bears upon said washer to compress the packing around said stem.

ALBERT C. LINDBLOOM.
